(57) **CLAIM**

The ornamental design for a foldable chair/table, as shown and described.

DESCRIPTION

FIG. 1 is a front perspective view of the foldable chair/table according to my new design configured as a chair;

FIG. 2 is a rear perspective view thereof;

FIG. 3 is a front elevational view thereof;

FIG. 4 is a right-side elevational view thereof, the left-side elevational view being a mirror image of FIG. 4;

FIG. 5 is a rear elevational view thereof;

FIG. 6 is a plan view thereof taken from above;

FIG. 7 is a plan view thereof taken from below;

FIG. 8 is a front perspective view of the foldable chair/table configured as a table;

FIG. 9 is a rear perspective view thereof;

FIG. 10 is a front elevational view thereof;

FIG. 11 is a right-side elevational view thereof, the left-side elevational view being a mirror image of FIG. 11;

FIG. 12 is a rear elevational view thereof;

FIG. 13 is a plan view thereof taken from above;

FIG. 14 is a plan view thereof taken from below;

FIG. 15 is a front perspective view of the foldable chair/table in a folded condition;

FIG. 16 is a rear perspective view thereof;

FIG. 17 is a front elevational view thereof;

FIG. 18 is a right-side elevational view thereof, the left-side elevational view being a mirror image of FIG. 18;

FIG. 19 is a rear elevational view thereof, this view being identical to that shown in FIG. 12;

FIG. 20 is a plan view thereof taken from above, the view being identical to that shown in FIG. 13;

FIG. 21 is a plan view thereof taken from below; and,

FIG. 22 is a rear perspective view thereof taken from below.
